UNITED STATES PATENT OFFICE.

BRUNO V. NORDBERG, OF MILWAUKEE, WISCONSIN.

PUMP FOR SUPPLYING FUEL TO INTERNAL-COMBUSTION ENGINES.

1,333,566.

Specification of Letters Patent.

Patented Mar. 9, 1920.

Application filed July 1, 1915, Serial No. 37,568. Renewed May 8, 1919. Serial No. 295,707.

To all whom it may concern:

Be it known that I, BRUNO V. NORDBERG, a citizen of the United States, residing at Milwaukee, in the county of Milwaukee and 5 State of Wisconsin, have invented certain new and useful Improvements in Pumps for Supplying Fuel to Internal-Combustion Engines, of which the following is a specification.

10 My present invention pertains to an improved pump for supplying fuel to internal combustion engines and to means for regulating the capacity of said pump.

Two embodiments of the invention are 15 illustrated, more or less diagrammatically in the annexed drawings, wherein:

Figure 1 is a longitudinal section of one form of pump embodying my invention;

Fig. 2 a detail plan view of certain portions thereof; and

Fig. 3 a sectional view embodying a modified form of the invention.

In internal-combustion engines of the high-compression type, the fuel has to be 25 forced into the cylinder by means of a pump, and such pump must be so constructed that it will automatically deliver to the cylinder the exact amount of fuel that is necessary for the load that the engine 30 carries, and such pump must be provided with a device whereby this amount of fuel may be varied to suit the variation of the load, giving the motor more fuel when the load increases and less fuel when the load 35 decreases.

It is also desirable and necessary that this regulating device should be under the control of an automatic governor, so as to render the engine self-regulating.

40 The most popular device used for regulating the capacity of the pump in accordance with the demand for fuel is a by-pass valve, whereby part of the fuel is ejected from the pump and turned back into the 45 supply, and another part of the fuel forced into the motor cylinder.

Fuel pumps embodying such construction have certain defects, which are eliminated by the present invention. Most pumps heretofore designed for forcing the charge into the engine are so arranged that the excess liquid fuel which the pump takes in during the suction stroke is discharged through a by-pass valve back into the supply, during 55 the first part of the discharge stroke and the remainder of the liquid fuel is then

forced into the motor cylinder when the by-pass valve is closed. In all such devices where the by-pass valve is held open during the early part of the discharge stroke 60 it is necessary that such valve be open during the latter part of the suction stroke so that the by-pass valve during the latter part of the suction stroke also acts as a suction valve. In fact, in all such devices of 65 which I am aware the suction valve can act as a by-pass valve when no separate by-pass valve is needed. See patent to Diesel No. 654,140, wherein the by-pass valve is opened during the latter end of the suction 70 stroke, and remains open during an equal part of the discharge stroke.

The liquid fuel is in most cases mineral oil, having considerable viscosity. If such fluid contains air or develops gases, and if 75 the mixture of oil and air is drawn into the pump, the pump will cease to work, unless the air can be readily discharged from the space confined by the valves and the plunger.

80 A fluid of high viscosity will not readily separate itself from air mixed therewith, and if the pump is provided with a by-pass valve as just described, that is, one that is kept open during the latter part of the suction stroke and the early part of the discharge stroke, the air may be expelled from the pump through the by-pass valve during the discharge stroke, but during the early part of the following suction stroke it will 85 be sucked back into the pump, and particularly where the fluid is of high viscosity, in which case, the air does not readily separate from the oil. This is a very disagreeable feature in pumps of this kind, particularly when such pumps are used on marine engines. In such engine installations the oil may be at times violently agitated by the motion of the ship, and if the air enters 90 the fuel pumps with the oil and does not readily separate, the engines will stop.

95 The main object of this invention is to completely overcome such difficulty, and this may be accomplished by various arrangements, two of which are illustrated, somewhat diagrammatically, in the drawings.

105 Referring first to Figs. 1 and 2, 1 denotes the driving shaft, provided with a crank 2 and fly-wheel 3, the latter shown in part only in Fig. 2. The crank has secured to it a connecting-rod 4, which at its inner end is 110 attached to a cross-head 6, fitting and work-

ing in the outer end of a hollow head or extension 7 of the pump body 8. The plunger or piston-rod of the pump is denoted by 9, and is provided at its inner end with a 5 piston or head 10, fitting within the bore of the suction chamber or cylinder 11 of the pump, the head being somewhat larger than the rod 9, and normally held in its outermost position, as shown in the drawings, by 10 a heavy spring 12, mounted within the hollow head 7, and bearing at its outer end against the inner face of a washer or disk-like member 13, secured to the outer end of the piston-rod. The fuel-supply chamber is 15 denoted by 14, the fuel being drawn therefrom through a pipe 15, past an intake or suction valve 16, which latter opens into a chamber or channel 17, extending from the pump cylinder 11. 18 indicates the discharge valve, which opens outwardly from the chamber 17 and controls the passage of the fuel to the engine cylinder through the discharge pipe or port 19. Valve 18 is 20 spring-loaded, as shown, and closes to its seat immediately the pressure exerted by the pump falls to that point where it will be overcome by the spring, and oil-pressure in port 19.

The by-pass port or channel is controlled 30 by two valves, a check-valve 20 and a by-pass valve 21, the latter moving inwardly to open, while the former moves outwardly to open. A pipe 22 leads from the by-pass channel back to the supply chamber 14. 35 Valve 21 is provided with a stem 23, having secured to its upper end a block 24, slidably mounted in a head 25, the valve being urged to its closed position by a spring 26. Mounted in the head is a rock-shaft 27, having secured to its inner end a tappet 28, the free end of which overlies block 24 and serves to move the same downwardly to open the valve 21, and to maintain it open for a predetermined interval of time. In operation, the 40 valve is opened at some point during the discharge stroke of the pump piston, and remains open during the early part of the suction stroke.

Suitable means is employed for operating 50 the tappet and to vary the time when it acts upon the block 24 to open the valve. The throw of the tappet remains practically constant for all variations in load, but the time at which it becomes operative varies with the 55 load, the contact being made earlier for a light load and later for a heavy load, so as to cut out the fuel earlier in the former case and later in the latter case. Any suitable means may be employed to accomplish this 60 result, and in the drawings I have shown the tappet shaft 27 connected by a lever or arm 29 to an eccentric strap 30, through a connecting rod 31. The position of the eccentric upon which the strap is mounted is 65 controlled by a pendulum governor, indi-

cated as a whole by 32, and operatively connected up with the fly-wheel 3 in the usual manner, so that the eccentric is advanced when the load is decreased. In other words, the position of the eccentric will be advanced 70 in relation to the position of the crank 2, and the cutting out of the fuel delivery by the earlier opening of the by-pass valve 21 will thereby take place earlier in the forcing stroke of the pump.

The operation of this form of pump is as follows: With the crank 2 in the position shown, all the valves are closed, and the cylinder 11 is filled with liquid fuel, the piston, in its outward movement under the action of 80 the spring 12, having drawn in a charge through the inwardly-moving suction valve 16. Upon a further rotation of the crank, cross-head 6 is moved inwardly and comes into contact with disk-like member 13, at 85 which time the cross-head is moving with considerable velocity, whereby a high velocity is imparted to the disk and the attached piston which, of course, forces the fuel from the pump past the eduction valve 90 18. The discharge of the fuel is quick, or practically instantaneous, which is highly beneficial when an atomizing device is employed to inject the fuel into the motor cylinder. 95

The eccentric is so set that the tappet 28 acts upon the by-pass valve at some point during the discharge stroke of the piston and by adjustment of the eccentric the point of opening can be regulated as may be necessary, opening early when a small quantity of oil is required, so that during the first part of the discharge stroke the oil is forced to the motor and during the latter part of the discharge stroke it is returned past the 100 check-valve 20 and by-pass valve 21, through pipe 22 to the supply tank 14.

It is plain that in this device the by-pass valve 21 will also be open during the early part of the suction stroke of the pump and that, in fact, the earlier it opens during the discharge stroke, the later it will close during the following suction stroke. The check valve 20 will, however, prevent the oil from flowing back through the by-pass valve into the pump as it seats toward the pump cylinder and, therefore, under no condition can the by-pass valve become in effect a suction valve. Consequently, if a quantity of oil charged with air is sucked into the pump, 110 part of this mixture will be driven out through the discharge valve 18 and pipe 19 into the motor cylinder and whatever remains will be later discharged through the by-pass valve and pipe 22 to the supply, but 120 during the suction stroke nothing that has passed the check valve 20 can return and, therefore, air can not accumulate in the pump.

It has been shown in practice that when 130

an excess of fuel drawn into the pump has to be brought up to quite a high pressure (in fact, a pressure higher than the working pressure of the engine) such condition 5 greatly assists in clearing the pump of air. Experience shows that when oil, highly charged with air, is drawn into the pump, and this oil, during the following discharge stroke is subjected to the pressure within the 10 engine, the air-bubbles are compressed, which, of course, reduces for the moment the quantity that passes through valve 18 and pipe 19. As soon, however, as the by-pass valve is opened, the expansive force of the 15 air acts in a manner which quickly clears the pump of air and prevents it from becoming air-bound. Thus, with a pump constructed in accordance with the present invention, the supply tank can be pumped dry 20 so that the motor actually slows down, but as soon as the supply tank is replenished the pump and motor resume their normal action. If the same thing should happen in devices 25 of the older type, the pump would become hopelessly air-bound, and would have to be primed before it would again be in condition to deliver oil to the motor.

In Fig. 3 a different embodiment of the invention is illustrated.

30 Similar members are similarly numbered as in Fig. 1, 14 being the tank, 15 the supply pipe, 16 the induction valve, 18 the eduction valve, and 19 the discharge port leading therefrom to the engine cylinder. The 35 check-valve 20 and by-pass valve 21 are also present, but are slightly modified in arrangement from those above set forth. The pump body or casing 8 is provided with an opening in which is mounted a piston or 40 plunger 33 operated from a crank 2 by a connecting rod or pitman 4.

34 denotes a rod slidably mounted in an opening in the pump casing 8, said rod bearing at its lower end upon the upper side of a block 35, to which there is secured a stem 36 carrying at its lower end the by-pass valve 21. The stem passes through a partition 37, and a spring 38, interposed between the partition and the lower face of the block 50 35, tends to draw the by-pass valve to its seat. The check-valve 20 in this instance is located above the by-pass valve and a spring 39 urges the check-valve to its seat. The upper end of rod 34 is pivotally connected 55 at 40 to a floating lever 41, one end of said lever being connected to the pump plunger 33 at the point 42. The opposite end of the lever is pivotally connected, as at 43, to one end of a link 44, the lower end of the link 60 being likewise connected to a lever 45 fulcrumed at 46 and controlled in its position by a ball governor 47.

Under this construction the movement of the rod 34 is approximately constant, but 65 the movement of the block 35 varies with

the position of the governor, for the reason that the amount of play between the rod and the block varies with the position of the governor. With the parts in the positions shown in full lines, the governor is 70 at its highest point, and as a consequence the amount of play between said rod and the block is at its minimum, whereby the by-pass valve 21 will be opened early in the ejecting stroke of the piston 33, and as a 75 consequence but a relatively small amount of oil will be forced into the engine through the eduction valve 18, the check-valve 20 opening and allowing the excess oil to return to the fuel supply tank 14. Immediately the 80 suction stroke begins the check-valve seats, preventing the drawing in of any oil, air, or mixed air and oil, through the by-pass valve, which at such time is still open. As will be readily appreciated, as the engine 85 slows down under increased load, the governor will shift the position of the floating lever 41 and consequently will increase the play between the rod or stem 34 and the block 35, and this results in a later opening 90 of the by-pass valve relatively to the stroke of the pump piston, thereby insuring the forcing of the proper quantity of oil to the engine.

The construction just described can be 95 used to advantage where means, other than the pressure exerted upon the fuel by the pump, as under the construction first set forth, is employed, to atomize the fuel as, for instance, compressed air at a pressure 100 considerably higher than that of the oil. In such case the office of the pump is simply to inject into the atomizer a certain quantity of oil very early in the stroke. Under both constructions the by-pass valve is prevented 105 by the check-valve from acting as a suction or induction valve and in each case the pump clears itself of air.

In the use of the term "piston" in referring to the members 10 and 33 it is to 110 be understood as denoting any element, whether it be a true piston or not, which acts to draw in and force the fuel from the pump chamber.

Having thus described my invention, what 115 I claim is:

1. A pump for forcing fuel into an internal-combustion engine, comprising in combination a piston; an eduction valve; an intake or suction valve; a by-pass valve 120 opening from the pump chamber and controlling a passage leading therefrom to the source of supply; and a check-valve acting to close such passage upon the completion of the ejecting stroke of the piston. 125

2. A pump for forcing fuel into an internal-combustion engine, comprising in combination a piston; an eduction valve; an intake or suction valve; a by-pass valve opening from the pump chamber and con- 130

trolling a passage leading therefrom to the source of supply; means, responsive to the requirements of the engine, for controlling the opening and closing of said by-pass valve; and a check-valve acting to close such passage upon the completion of the ejecting stroke of the pump piston aforesaid.

3. A pump for forcing fuel into an internal-combustion engine, comprising in combination a piston; an eduction valve; an intake or suction valve; a check-valve controlling the reverse flow of fuel through a channel leading from the pump chamber and normally seating during the suction of the piston; and a governor-controlled by-pass valve, regulating the discharge of fuel through said channel.

4. A pump for forcing oil into an internal-combustion engine, comprising in combination, a piston; an intake valve; an eduction valve; and means for controlling the amount of fuel forced by the piston through the eduction valve, said means being under the control of and actuated by the engine and serving to eject the remaining portion of the fuel and the entrained or contained air from the pump thereby preventing accumulation of air in the pump and consequent air binding thereof.

5. In an apparatus for supplying a variable quantity of fuel to an internal-combustion engine, the combination with the fuel supply; of fuel-forcing means communicating therewith and supplying at the beginning of each working stroke of the engine an excess of fuel under pressure greater than the back pressure of the engine; and means under the control of the engine for allowing the excess fuel, still under pressure, to return to the fuel supply during the latter portion of the feeding or supplying stroke of the fuel-forcing means.

6. In an apparatus for supplying a variable quantity of fuel to an internal-combustion engine, the combination with the fuel supply; of a pump operated by the engine, the pump-chamber being provided with a suction valve, a fuel feed valve, and a by-pass valve, the by-pass valve normally opening at a pressure equal to or greater than that existing in the engine cylinder; and means for preventing a return flow of fuel into the pump past the by-pass valve during the suction stroke of the pump.

7. In an apparatus for forcing fuel into an internal combustion engine, the combination of a pump piston; means for imparting a suction stroke thereto and opposing the inward movement thereof; a reciprocating member normally spaced away from the piston; means for actuating said member and bringing it into contact with the piston under high initial speed and to im-

part a fuel-ejecting stroke thereto; and a by-pass valve opening only during the latter part of the ejecting stroke of the piston and closing during the suction stroke thereof.

8. In an apparatus for forcing fuel into an internal-combustion engine, the combination of a pump piston; means for imparting a suction stroke thereto and opposing the inward movement thereof; a reciprocating member normally spaced away from the piston; means for actuating said member and bringing it into contact with the piston under high initial speed and to impart a fuel-ejecting stroke thereto; a by-pass valve opening during the ejecting stroke of the piston and closing during the suction stroke thereof; and a check-valve preventing influx of fuel past the by-pass valve during the suction stroke of the piston.

9. In an apparatus for forcing fuel into an internal-combustion engine, the combination of a pump piston; means for imparting a suction stroke thereto and opposing the inward movement thereof; a reciprocating member normally spaced away from the piston; means for actuating said member and bringing it into contact with the piston under high initial speed and to impart a fuel-ejecting stroke thereto; a by-pass valve opening only during the latter part of the ejecting stroke of the piston and closing during the suction stroke thereof; and means under the control of the engine for timing the opening and closing of the by-pass valve.

10. In an apparatus for forcing fuel into an internal-combustion engine, the combination of a pump piston; means for imparting a suction stroke thereto and opposing the inward movement thereof; a reciprocating member normally spaced away from the piston; means for actuating said member and bringing it into contact with the piston under high initial speed and to impart a fuel-ejecting stroke thereto; a by-pass valve opening during the ejecting stroke of the piston and closing during the suction stroke thereof; a check-valve preventing influx of fuel past the by-pass valve during the suction stroke of the piston; and means under the control of the engine for timing the opening and closing of the by-pass valve.

11. In an apparatus for forcing fuel into an internal-combustion engine, the combination of a pump; and a reciprocating actuating element for said pump, operated from the engine, said element and pump having a lost-motion connection whereby the actuating element may take on a high initial speed prior to actuating the pump.

12. In an apparatus for forcing fuel into an internal-combustion engine, the combina-

tion of a pump; a moving actuating element for said pump operated from the engine, said element and pump having a lost-motion connection whereby the actuating element 5 may obtain a high initial speed prior to actuating the pump; a by-pass valve for the pump, opening only during the latter por-

tion of the discharge stroke of the piston; and means controlled by the operation of the engine for timing the opening and closing of the by-pass valve. 10

In testimony whereof I have signed my name to this specification.

BRUNO V. NORDBERG.
